UNITED STATES PATENT OFFICE.

WILLIAM H. BRADLEY AND GEORGE W. BRADLEY, OF PHILADELPHIA,
PENNSYLVANIA.

DESIGN FOR A HORSESHOE.

SPECIFICATION forming part of Design No. 35,002, dated August 27, 1901.

Application filed July 15, 1901. Serial No. 68,441. Term of patent 14 years.

To all whom it may concern:

Be it known that we, WILLIAM H. BRADLEY and GEORGE W. BRADLEY, citizens of the United States, and residents of Philadelphia, Pennsylvania, have invented and produced a new and original Design for Horseshoes, of which the following is a specification, reference being had to the accompanying drawings, forming part thereof.

Figure 1 is an inverted plan view of a horseshoe, showing our new design. Fig. 2 is a side elevation thereof. Fig. 3 is a sectional view taken on the plane indicated by the dotted line X X in Figs. 1 and 2, and Fig. 4 a section in the plane indicated by the dotted line Y Y in Figs. 1 and 2.

As shown in the drawings, the leading or material feature of our design consists in the series of cruciform calks 1, having fillets 2,

uniting them with plate 3 of the shoe in the 20 internal angles 5 of the calks. The calks 1 are disposed or arranged as shown in Fig. 1 and have their extremities terminating in the same plane, the said calks and fillets 2 being formed integrally with the plate 3, and the 25 plate 3 on its surfaces in the interspaces 4 between the calks being convex, as shown in the section in Fig. 4.

Having described our invention, what we claim as new, and desire to secure by Letters 30 Patent, is—

The design for a horseshoe as herein shown and described.

WM. H. BRADLEY.
GEO. W. BRADLEY.
